SHOE WITH ELASTIC THROAT

Bruno Oliva, St. Albans, N. Y.

Application July 20, 1938, Serial No. 220,352

2 Claims. (Cl. 36—51)

This invention relates to footwear and more particularly refers to improvements in ladies' shoes of the high-heeled pump type.

It is well known that an essential requirement of shoes of the pump type is a perfect fit, coupled with an elegance of line which calls for the top marginal edge of the shoe to exactly conform to and snugly hug the contour of the foot of the wearer.

As a rule, the required perfect fit and attractive appearance of high-heeled pumps and slippers are obtained only at the cost of considerable discomfort to the wearer because the throat of the shoe tends to cut into the instep of the foot, at times causing acute pain and a swelling of the flesh, which is of itself objectionable because it mars the appearance of a well groomed foot.

Accordingly, the main object of my invention is to provide, in a lady's pump or slipper, a novel and improved construction of throat, which, while conforming snugly to the shape of the foot, will not cause any discomfort to the wearer.

Another object is to provide a novel and improved high heeled lady's pump, having a yielding throat, constructed so as to be practically indistinguishable from an ordinary throat, and insuring the graceful lines which are so essential in a shoe of the better type.

A further object is to provide in a lady's pump or slipper a novel and improved construction of throat, whereby the edge of the shoe will not cut into the instep of the wearer, said throat being made out of leather harmonizing with the rest of the shoe upper, but being elastic, so that while the leather will be capable of stretching it will also be capable of contracting in order to at all times hug the foot of the wearer and preserve the elegance and attractiveness of the shoe.

Other objects and advantages of the present invention will more fully appear as the description proceeds and will be set forth and claimed in the appended claims.

My invention is illustrated by way of example in the accompanying drawings, in which:

Fig. 1 is a view in perspective of a pump embodying my invention.

Fig. 2 is a top plan view of the upper used in the pump shown in Fig. 1, minus the vamp;

Fig. 3 is a plan view of the reverse side thereof;

Fig. 4 is a fragmentary top plan view in an enlarged scale of the throat portion of the upper shown in Fig. 2;

Fig. 5 is an end view in elevation of the same;

Fig. 6 is a fragmentary plan view in an enlarged scale of the forward end of Fig. 3;

Fig. 7 is a fragmentary plan view of the upper used in the pump shown in Fig. 1 including the vamp;

Fig. 8 is a top plan view of the upper used for making a pump similar to that shown in Fig. 1, in which the vamp is in one piece with the body of the upper;

Fig. 9 is a plan view of the reverse side thereof, and

Fig. 10 is a fragmentary longitudinal section in an enlarged scale through line 10—10 of Fig. 7, showing the construction of the throat.

Referring to Fig. 1 it will be seen that the shoe comprises the usual heel 20, the sole 21 and quarter 22, and the vamp portion 23 sewed to the quarter portion of the upper at 24. The upper has a top marginal edge 25 which is relatively non-stretchable, said top edge being finished if desired with the usual small beading or piping 26 which is obtained by sewing a tape 27 along the edge 25 to the outer surface of the upper and then folding it around the edge against the inner surface of the upper and to be finally held in position by once more stitching it between the upper and the lining.

Said beading at the front stops short of the throat, which throat 28 is formed from a separate piece of elastic material, preferably elastic leather, which is applied to the upper in the manner that I will presently describe.

Referring to Figs. 2 to 5 it will be seen that the quarter portion of the upper is composed of two halves 29, 30 joined at the front end by a piece of elastic material 31.

In the drawings, Figs. 3 and 6, said piece of elastic material is shown as being composed of a layer 32 of thin and therefore stretchable leather and another layer 33 of elastic fabric, preferably a fabric of the type where the weft is composed entirely of elastic threads and the warp entirely of inelastic threads so that the fabric is stretchable only in the direction of the weft that is, in the present case, transversely of the shoe.

Said elastic piece 31 is somewhat wider from side to side than the distance separating the front end portions 34, 35 of the two halves 29, 30. Said end portions 34, 35 are relatively narrow and curved towards the front so as to produce the two curved ends of the throat shown in Fig. 1.

Said elastic piece 31 is also wider in a front to rear direction than the extreme end edges 36, 37 of front portions 34, 35 of the quarter portion of the upper. The two halves 29, 30 are placed side by side at the proper distance from each other and the piece 31 is placed at the front end

thereof against their inner surface so that its side marginal edges will overlap a small width along the edge of the inner surface of front portions 34, 35.

5 The marginal edge portions of said piece 31 adjoining the end edge portions 36, 37 will then be stitched thereto as shown at 38, 39 in Figs. 5 and 6, and the rear portion 31' of said piece 31 is left loose with respect to the inner edges of 10 said portions 34, 35.

The contour of the thus completed front edge of the quarter portion of the upper is adapted to substantially register with the contour of the rear edge of the vamp which is to be stitched thereto 15 along the line 24, as will be understood, so as to form the completed upper shown in Fig. 7.

The inner edge of the vamp will naturally overlap the front edge of the quarter portion of 20 the upper so that it may be stitched thereto, the central portion of the rear edge of the vamp being indicated by the dot and dash line a—a in in Fig. 4.

In order to form the throat the elastic piece 31 is inwardly folded along the transverse line b—b 25 shown in Fig. 4, said line connecting the inner ends of the stitching lines 38, 39. Said line b—b will therefore define folded edge 40 of the throat, said edge 40 being in continuation of and completing the marginal edge portion of the shoe.

30 Referring to Fig. 10 it will be seen that the inwardly folded throat portion 31' of piece 31 is wide enough in a front to rear direction to cause its rear edge 31'' to reach below the outer front edge of piece 31 when said portion 31' is folded.

35 The lining 41 and if desired also an intermediate fleece doubler 42 are applied against the rear surface of the upper and secured by stitching thereto as indicated at 43, the stitching going right through the thickness of folded piece 31 40 positioned between the upper and the lining.

45 As a result the throat will consist of a relatively narrow folded strip of double thickness of elastic material joining the two end edges 36, 37 of said pieces 29, 30, said strip forming an integral part of the general outline of the shoe and being nearly indistinguishable in appearance from the throat of an ordinary shoe.

However, the elasticity of the material employed in thus producing the throat will cause 50 said throat to be yielding without cutting into the instep while at all times closely abutting against the instep as necessitated by the requirements of a perfect fit. The folded edge of the throat is smooth and rounded and, therefore, 55 there is no sharp edge hugging and cutting into the instep. The result is a very comfortable yet close fitting shoe. Furthermore the folded edge of said throat greatly enhances the finished appearance of the shoe because no raw or sharp 60 edges are exposed.

65 It will of course be understood that the layer of leather 32 forming part of elastic 31, will match the leather used for the rest of the upper, unless a different color effect should be desired in which case said part 32 may be of a different color.

70 It is within the scope of my invention to make the visible part 32 of piece 31, constituting the throat, of elastic material other than leather, although for producing the appearance of a finished shoe of graceful design and appearance leather is to be preferred.

75 My invention can also be applied in connection with shoes in which the vamp is formed integral

with the rest of the upper, as shown in Figs. 8 and 9.

In said figures the upper 44 is cut between its two side portions 45, 46 forming the top marginal portion 47 of the upper, the front end of the two sides of said marginal portion being slightly curved inwardly as shown at 48, 49 in order to eventually provide a curved juncture between the ends of the top marginal portion and the throat, and then the cut extends a certain distance forwardly as shown at 50, 51 in dove-tailed arrangement, the forward ends of said portions 50, 51 being joined by a slightly rounded transverse cut at the front shown at 52.

The elastic piece 31 is then applied against the 15 rear surface of the upper at the front end of the marginal edge, causing the edges of the front part of said elastic piece to overlap to a certain extent corresponding parts of the edges of the cut 48, 49, 50, 51, 52.

20 Said elastic piece 31 is then stitched to the upper in proximity of portions 50, 51, 52 of the cut, leaving the rear portion of said elastic piece overlapping the rounded portions 48, 49 of the cut, unstitched.

Said unstitched portion is then folded reversely against the inner surface of the upper along a transverse line passing through the points where the curved portions 48, 49 and the spreading portions 50, 51 of the cut meet, said line corresponding to the line b—b shown in Figs. 4 and 6. Said folded portion is then stitched or cemented in place between the upper and the lining, as previously explained, thus forming an elastic throat 30 similar to that shown at 28 in Fig. 1 the edge of which will be in exact alignment with and will form a continuation of the side edges of the top marginal edge produced by cut 47. The top marginal edge may be finished if desired by applying a binding or tape to it in order to form the small 40 beading or piping around the edge in the customary manner, as previously explained.

In this latter construction the elastic throat 45 will appear as a relatively narrow strip extending transversely between lines 50 and 51, its appearance being substantially the same as that shown in Fig. 1.

It will be understood by those skilled in the art that many specific details relating to the 50 art of making shoes generally, may vary from those shown and described without affecting the scope of my invention and without departing from the inventive idea.

The drawings should, therefore, be understood as being intended for illustrative purposes only 55 and not in a limiting sense.

I, accordingly, reserve the right to carry my invention into practice in all those ways and manners which may enter, fairly, into the scope of the 60 appended claims.

I claim:

1. A shoe of the pump type comprising an upper having an unyielding tapered edge extending rearwardly from a point at each side of the throat, said upper being cut forwardly a relatively short distance from each of said points so as to form a relatively narrow transverse gap ahead of an imaginary line joining the said two points, and a folded piece of flexible elastic material interposed between and joining the edges 65 formed by said forwardly directed cuts so as to fill said gap, the folded edge portion of said piece extending between the said two points and having its surface exposed at both the front and rear to allow full play to its elastic properties, 70 75

the folded edge of said portion preventing the throat from cutting into the instep, and providing an unbroken continuity of the top marginal edge of the throat, interrupted by said gap.

- 5 2. A shoe of the pump type comprising an upper having an unyielding top marginal edge extending rearwardly from a point at each side of the throat, said upper being cut forwardly a relatively short distance from each of said 10 points so as to form a relatively narrow transverse gap ahead of an imaginary line joining the said two points, said gap having a substantially uniform depth, and a folded piece of flexible elas-

tic material interposed between and joining the edges formed by said forwardly directed cuts so as to fill said gap, the folded edge portion of said piece extending between the said two points and having its surface exposed at both 5 the front and rear to allow full play to its elastic properties, the folded edge of said portion preventing the throat from cutting into the instep, and providing an unbroken continuity of the top 10 marginal edge of the throat, interrupted by said gap.

BRUNO OLIVA.
